CLAIM

The ornamental design for eyewear front, as shown and described.

DESCRIPTION

FIG. 1 is a front perspective view of an eyewear front showing my new design;

FIG. 2 is a front elevational view thereof;

FIG. 3 is a rear elevational view thereof;

FIG. 4 is a side elevational view thereof;

FIG. 5 is a top plan view thereof; and,

FIG. 6 is a bottom plan view thereof.

The portion of the figures in broken lines is shown for environmental purposes only and forms no part of the claimed design.
